Patented Feb. 26, 1918.

UNITED STATES PATENT OFFICE.

HARRY C. TURNER AND WILLIAM A. TUFTS, OF LOS ANGELES, CALIFORNIA.

TENNIS-COURT MARKER.

1,257,768.

Specification of Letters Patent. Patented Feb. 26, 1918.

Application filed December 1, 1915. Serial No. 64,393.

To all whom it may concern:

Be it known that we, HARRY C. TURNER and WILLIAM A. TUFTS, citizens of the United States, residing at Los Angeles, in 5 the county of Los Angeles and State of California, have invented certain new and useful Improvements in Tennis-Court Markers, of which the following is a specification.

This invention relates to improvements in 10 marking devices, and particularly boundary or line marking means, such for instance as may be employed in marking the lines of tennis or other game courts or boundaries of any kind.

15 It is an object of the invention to provide a metallic line or boundary mark adapted to be placed upon the surface of the earth, pavement or other surfaces and to be anchored thereto in such a way as to not be 20 readily displaced.

25 It is a further object of the invention to provide a boundary or line marking device made up of flanged or channel metal set so that the flanges thereof will be embedded in the earth, concrete or other surface upon 30 which the boundary lines are to be marked, means being provided for preventing longitudinal or lateral shifting movement of the metallic pieces forming the device.

35 It is a still further object of the invention to provide a line or boundary marking structure for tennis or other courts or other areas to be bounded, made up of a series of metallic sections adapted to be laid upon the ground and having interlocking connecting portions for firmly holding the said sections together.

40 With these and other objects in view the invention comprises certain novel constructions, combinations and arrangements of parts as will be hereinafter more fully described and claimed.

In the accompanying drawing:

45 Figure 1 is a top plan view of a portion of a tennis court marker or boundary indicating device, a portion of one of the side lines, one of the alley lines and one of the end lines of the court being illustrated and with parts thereof broken away.

50 Fig. 2 is a transverse sectional view upon an enlarged scale taken upon the line 2—2 of Fig. 1.

55 Fig. 3 is a detail sectional view upon an enlarged scale taken upon the line 3—3 of Fig. 1.

Fig. 4 is a detail sectional view taken upon the line 4—4 of Fig. 1.

Fig. 5 is an enlarged detail plan view of the adjacent ends of the marker or sections, the parts being somewhat separated. 60

Fig. 6 is a fragmentary detail sectional view through the adjacent sections of the marking device showing the manner of locking them together.

Various marking means for tennis courts, 65 game grounds or for marking lines on other areas, have been heretofore used but usually with the difficulty that they are not lasting and have to be repeatedly renewed, especially in tennis courts where the lines are 70 stepped upon frequently. The common expedient of using lines made by dusting lime upon the court surface has proven very ineffective, the lines sometimes having to be renewed during game time. Markers or 75 line indicators made of ribbon or fabric such as canvas or the like while more durable wear out in a short time and frequently become rolled so as to readily catch upon the feet of the players and cause considerable 80 difficulty. With the device of the present invention a very permanent line or marker is produced and one which is readily put in place and can be positively held against displacement without difficulty. An approved 85 form of the device has been illustrated in the accompanying drawing in which 5 indicates a section of the marking device, the said device being usually made of a series of sections like the same or similar thereto. 90

Each of said sections is preferably made of a metallic strip usually bent, rolled or otherwise shaped to form a channel bar having depending side edge flanges 6 adapted to be embedded in the earth, concrete, asphalt or 95 other material of which the court or surface to be marked may be formed. The channel shape of the strips give them great longitudinal stiffness and absolute straightness even though they are made of comparatively thin material such as galvanized iron or the like. The sections commonly employed are usually made with an elongated tongue 7 at one end thereof, having tapering side edges 8 and having the flanges 100 6 cut back for the length of the said tongue. The other end of each section is provided with a slot 9 adapted to receive the tongue 7 of an adjacent section. The flanges 6 of this end of the section are allowed to pro- 105 110

ject at 10, a short distance beyond the body portion of the section. The projections 10 being bent in slightly will pass beneath the body portion of the section next adjacent thereto and within the ends of the flanges 6 thereof as clearly shown in Figs. 1 and 6 of the drawing. The tongue 7 is then usually bent backwardly beneath the body portion of the adjacent section as shown in said Fig. 6 to form a positive lock between the two sections. The two sections are thus positively held with respect to each other, the bent tongue preventing movement in one direction while the shoulders of the sections engaging each other at the projections 10 prevent movement in the other direction. The bent portion of the tongue within the slot 9 also positively holds the section against movement in either direction. The tongue 7 passes above the body portion of one section while the projections 10 slip beneath the body portion of the other section, thus making a very stiff and strong joint between the parts.

In marking a tennis court a single piece of marking material might of course be made to reach entirely across the court or longitudinally thereof if preferred. This is not generally the case however as it is far preferable to form the marking device of the short sections applied end to end for making up the desired length of the longitudinal and transverse lines of the court. At intermediate points along each section, the metal is preferably perforated as at 11 so that wire or other nails or pins 12 may be driven through the perforations and into the ground or other surfaces upon which the marker is to be laid, for firmly holding the same in place and against any longitudinal or vertical displacement. The metal of the marker sections is preferably depressed around said apertures 11 to form countersunk recesses 13 to accommodate the heads of the nails 12 so that they will not project above the upper surfaces of the sections and form obstructions upon the device.

Where the joints in the device are intermediate the length of the lines of the court, they are made as above described. Where lines come together at an angle, as for instance where the transverse lines meet the longitudinal lines a similar joint is formed, the tongue upon the ends of one section being used as before but being slipped into slots 14 made longitudinally of the sections instead of transversely thereof. In this case the ends of the flanges 6 abut against the sides of the flanges on the member which extends across the end of the section carrying the tongue, as will be clearly understood by reference to Fig. 1 of the drawing. The tongues 7 are bent backwardly beneath the body portion of the transverse marking piece as clearly shown in Fig. 3 of the draw-

ing. It will be evident that the sections upon either side of the court which abut against other sections extending at an angle thereto should be made with a tongue adapted to slip into a slot as just described with respect to the joints shown in Fig. 3 of the drawing. In corner sections as for instance the sections brought together at the corner shown in Fig. 1, the end of one of the sections, as for instance 15 is also provided with a flange portion 16 turned down at the end of the section transversely thereof.

When using the device for a tennis court marker, it will be evident that a substantial metallic frame of rectangular form with suitable cross and intermediate lines is formed, the frame being very thoroughly braced in all its parts, and materially stiffened at its connecting portions to form a permanent and strong structure. In putting such frame in place, its component parts are preferably joined as above described and the frame is then properly located upon the ground, grass or other surface which have previously been wetted to receive it, and a roller, such as is commonly used for leveling the court is then passed over the said metallic pieces whereby they are embedded in the ground or sod and brought flush with the surface thereof. The flanges 6 and 16 will be embedded in the ground as shown in Figs. 2 and 3 for gapping and holding the frame in position. Any desired number of nails or pins 12 may then be driven through the apertures 11 for further and more effectively anchoring the marking structure in position. A metallic marker of this kind possesses many advantages in addition to its durability. In the first place it may be painted white or some other color which will stand out plainly, the metal affording an excellent surface for holding the paint. The lines formed by the marker sections also have their edges slightly rounded by the turning down of the flanges 6 and offer no chance for the catching of the foot upon the said sections and the flanges in addition to assisting in holding the sections from any lateral movement, render the sections stiff and not likely to become bent.

It will be evident that other shapes of metallic strips may be employed within the spirit of this invention and that the structure of the joints between the sections thereof may be considerably varied within the scope of the said invention.

In marking of boundaries of any kind where the parts are to be set in angular relation to each other, the holding slots 9 or 14 may be set to accommodate the position of the parts and the direction of lines.

What is claimed is:

1. A metallic boundary marker comprising pieces having securing edge flanges thereon adapted to be embedded in the ma-

terial to be marked, and connecting means joining said pieces whereby substantially continuous boundary lines may be marked.

2. A line marker comprising metallic channel pieces and means for connecting the same to afford a substantially continuous line marking means.

3. A line marker comprising sheet metal pieces having ground penetrating edge portions and connecting means for holding said pieces against relative movement in any direction with respect to each other.

4. A tennis court marker made up of a series of channel bar sections having tongue and slot connections at their ends.

5. A tennis court marker made up of a series of channel bar sections having their edge flanges turned downwardly and embedded in the surface to be marked, interlocking means between the sections preventing a relative movement between the parts in any way, and intermediate anchoring means also adapted to be embedded in the material of such surface.

6. A tennis court marker comprising a series of sections having a channel shape in cross section, one end of each section having a tongue while the other end thereof is provided with a tongue receiving slot and projections adapted to bear upon the end surfaces of adjacent sections whereby a stiff joint is formed between the parts, the tongues being bent to positively lock the sections together.

7. A marker for tennis courts comprising channel bars their upper surfaces being flush with the ground and having perforations in their body portions, anchoring nails driven

through said apertures, the said apertures being countersunk around the said nails for accommodating the heads thereof, and interlocking means forming substantially continuous channel bars.

8. A boundary marking structure comprising metallic pieces adapted to be set at angles to each other, one member having a locking tongue and the other being provided with slots extending approximately longitudinally thereof for receiving said locking tongues and abutment members for holding the parts in proper relation to each other.

9. A line marker comprising a series of sheet metal pieces having ground engaging edge portions and separable hooking portions connecting the adjacent ends of said pieces.

10. A line marker comprising a series of sheet metal pieces and having ground penetrating edge portions for holding the pieces against lateral and longitudinal movement and having bent down end portions for holding the said pieces against movement with respect to each other.

11. A line marker comprising sheet metal pieces having separable connecting means adapted to prevent adjacent ends of the pieces from being elevated or depressed with respect to each other.

In testimony whereof, we have hereunto set our hands in presence of two witnesses.
